UNITED STATES PATENT OFFICE.

IZYDOR GREBOWIEC, OF HOMESTEAD, PENNSYLVANIA.

PONTOON.

Application filed October 15, 1926. Serial No. 141,837.

The present invention relates to a pontoon particularly adapted for lifting sunken vessels and the like.

The important object of the invention lies in the provision of a pontoon of this nature which may be sunk practically full of water and when properly disposed is constructed so that an explosion may take place therein for forcing the water from the pontoon to make the same buoyant.

Another very important object of the invention lies in the provision of a pontoon of this nature with an exceedingly simple construction which will prove thoroughly reliable and efficient in operation, comparatively inexpensive to manufacture, strong and durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a longitudinal section through the pontoon embodying the features of my invention.

Fig. 2 is a longitudinal section through one end of the pontoon showing one of the pistons in an exploded position.

Fig. 3 is a detail section through one of the pistons.

Referring to the drawing in detail it will be seen that the numeral 5 denotes an elongated cylinder which is divided into two compartments by a central partition 6. The cylinder is provided with openings 7 adjacent the partitions 6 having suitable closures 8 which are held in place by fastening means 9 of any convenient type. Rings 10 are provided with annular flanges 11 which are engaged with the ends of the cylinder 5 by suitable means 12. These rings support cushion springs 14 extending inwardly of the cylinder. Casings 15 are mounted adjacent the ends of the cylinder 5, there being at least two and preferably four casings 15 adjacent each end and these casings house spring-pressed catches 16 which are normally held extended through openings 17 in the cylinder 5. The cylinder 5 is provided with openings 18 between the rings 10 and the casing 15. Pistons 20 are slidable in the compartments of the cylinder 5 and suitable packing rings 21 associated therewith.

In using this device the pistons 20 are located as shown in Figure 1, that is, adjacent the openings 7 so as to form powder receiving compartments between the partitions 6 and the pistons. The powder, or any other suitable explosive is packed or placed in these compartments as is apparent by the removal of the covers 8. After the explosives have been stored in these compartments the covers are placed on again and the pontoon is ready to be sunk alongside of the vessel or the like. It will be seen that as the cylinder is immersed in the water the major portion thereof will fill with water. Now in the compartments between the partitions 6 and the pistons 20 there may be located primed fuses or the like which will cause an explosion at the proper time, drive the pistons outwardly to the end, thereby forcing ahead of them the water from the compartments and the piston will be caught by the catches 16 and held in the position clearly shown in Fig. 2. It will be seen that the buffer springs 14 will function when hit by the piston. If desired, a closure plate 23 may be mounted at the end of the cylinders by attachment to the rings 10. Such a plate is shown in Figure 2. This plate, however, is not of the essence of the invention.

In using this pontoon, all openings are sealed before the same is placed in the water in order that it will be buoyant so as to be easily towed to any point desired. When the pontoon is in proper position to be submerged, these seals are removed, broken, or otherwise destroyed so that pontoon may sink as desired.

It is thought that the construction, operation, and advantages of this invention will now be clearly understood without a more detailed description thereof. It is apparent that numerous changes in the details of construction, and in the combination and arrangement of parts may be resorted to without departing from the spirit or scope of the invention as hereinafter claimed or sacrificing any of its advantages.

Having thus described my invention what I claim as new is:

1. A pontoon of the class described including a hollow body, a piston slideable in the body, said body provided at one end with an opening and a closure therefor so

that powder may be stored therein, buffer means at the other open end of the pontoon and catch means at said last-mentioned end.

2. A device of the class described including, in combination, a cylinder, a piston slidable in the cylinder, said cylinder having an opening, a closure associated with said opening, other openings provided in the cylinder, and catch means adjacent the other

10 openings.

3. A device of the class described including, in combination, a cylinder, a piston slidable in the cylinder, said cylinder having an opening, a closure associated with said opening, other openings provided in the cylinder, catch means adjacent the other openings, and buffer means adjacent said attachment.

In testimony whereof I affix my signature.
IZYDOR GREBOWIEC.
